ANTHONY E. CARLSON, OF LOS ANGELES, CALIFORNIA

REDUCING AND MASSAGING DEVICE

Application filed May 23, 1927. Serial No. 193,425.

This invention relates to massaging devices. By massaging the fleshy parts of the body it is possible to break down the fat tissues and increase the circulation of the blood 5 so that a reducing of the massaged portion takes place.

An object of the invention is to provide a massaging device which alternately compresses and releases the flesh so that the fat 10 tissues are broken down.

A further object of the invention is to provide a massaging device which operates by swinging in an arcuated path.

A still further object of the invention is 15 to provide a massaging device which presses resiliently against the body.

It is a further object of the invention to provide a massaging device of the character mentioned which is mechanically operated.

Other objects and advantages of the invention will be made evident hereinafter.

Referring to the accompanying drawings in which the invention is illustrated:

Fig. 1 is a view illustrating the utility of 25 the invention.

Fig. 2 is an enlarged elevational view partly sectioned.

Fig. 3 is a front elevational view of the 30 massage-unit of the invention.

Fig. 4 is a section taken as indicated by the line 4—4 of Fig. 2.

Fig. 5 is a section taken as indicated by the line 5—5 of Fig. 2.

Fig. 6 is a cross section taken as indicated 35 by the line 6—6 of Fig. 2.

Fig. 7 is an elevational view of an alter- 40 native form of the invention.

Fig. 8 is an enlarged fragmentary section of the invention taken on the line 8—8 of

Fig. 7.

Fig. 9 is a plan view of Fig. 7 on a smaller scale.

The form of the invention shown in Figs. 1 to 6 inclusive has a vertical guide 11 which 45 may be secured to any suitable support such as a wall by brackets 12. The case 13 of the invention has bosses 13^a which surround the guide 11 and are slidable thereon. A clamp-screw 13^b is provided for locking the case 50 13 in a suitable position. The case 13 sup-

ports the motor 14 of the invention at its upper part. The motor-shaft 15 extends downward from the motor 14 into the interior of the case 13 and has a worm-gear 16 secured thereon. The worm-gear 16 55 meshes with the worm-wheel 17 which is enclosed by the case 13, and when the motor 14 is in operation the worm-wheel 17 is rotated. As shown best in Fig. 6, the worm-wheel 17 is locked to a shaft 18 which journals in side-plates 19 of the case 13. The outer ends of the shaft 18 has eccentric plates 20 secured thereto which form the crank of the invention. The plates 20 carry crank-pins 21 to which links 22 of the invention 60 are pivoted. The lower ends of the links 22 are connected by a pivot 24 to an upper extension 25 of a pivot-member 26.

The pivot-member 26 is pivoted by a bolt 29 to the lower part of the case 13. The 70 forward part of the pivot-member 26 has a socket 30 into which a plunger 31 is extended. The plunger 31 is restrained from rotation by means of a pin 32 carried by the pivot-member 26 which extends into an axial 75 slot 33 formed in the plunger 31. A stem 35 is extended from the plunger 31 and through an opening 36 which connects to the bottom of the socket 30. A nut 38 is screwed onto the extending end of the stem 35 for 80 preventing the plunger 31 from being removed from the socket 30. In the socket 30 between the inner end of the plunger 31 and the bottom of the socket is compressed a spring 39 which tends to hold the plunger 85 at all times in the position shown in Fig. 2. Carried by the plunger 31 is the massage-unit 41 of the invention.

The massage-unit 41 has an arm 42 which extends into a slot 43 formed in the outer 90 end of the plunger 31. The arm 42 has a central recess 43 which provides forks, these forks extending around pins 44 which extend across the slot 43. This arrangement permits the arm 42 to be slid axially from engagement with the plunger, but prevents any radial movement. The outer pin 44 is provided with a nut 45 so that the portions of the plunger 31 surrounding the slot 43 may be clamped against the end of the arm 42 so 95 100

that the parts are rigidly attached together. The outer end of the arm 42 carries the back 47 of the massage-unit 41. Side-plates 48 are connected to the edges of the back 47 in any suitable manner such as by riveting or by welding. Supported by the side-plates 48 are shafts 49. The shafts 49 extend parallel to each other and are arranged on an imaginary arcuated line indicated at 50, which is generated around the center of the pivot-bolt 29. The shafts 49 carry rollers 51 which are separated by spacers 52. The peripheries 53 of the rollers 51 are preferably semi-cylindrical in cross section. As illustrated best in Fig. 3, the rollers 51 of adjacent shafts 49 are disaligned and preferably overlap.

In utilizing the invention just described, the motor 14 is energized so that the massage-unit 41 is moved through an arcuated path. 20 This is done by the links 22 swinging the pivoted arm which carries the massage-unit. As shown in Fig. 1, the massage-unit 41 is adjusted to such a height that the stomach of a patient 60 is being massaged. As the 25 massage-unit swings through the arcuated path, the flesh over which it operates is alternately compressed and released. The flesh is compressed horizontally and also vertically. As shown in Fig. 1 the flesh between the rows of rollers is compressed and forced 30 upward and downward so as to provide bulges 61. In Fig. 5 the dotted line 62 represents the manner in which the flesh is compressed in a horizontal plane. When the 35 massage-unit moves upward from the position shown in Fig. 5 so that the row of rollers below moves into the plane of the rollers shown in cross section, the high portions of the line 61 will be forced downward, and the 40 low portions of the flesh will be allowed to move upward. In other words, the rollers are so arranged that the adjacent portions of an area being worked upon are alternately compressed and released by a sort of kneading 45 action such as takes place when a baker is kneading bread.

The shafts 49 are placed in arcuated arrangement as illustrated in the drawings so that when the massage-unit is swung up and 50 down through an arcuated path, the upper and lower rollers will not protrude outward beyond the others as would be done if the rollers were in the same plane. This will be clearly seen from Fig. 1.

55 The plunger, socket and spring arrangement is provided so that the patient may press the massage-unit 41 inward which will result in a resilient pressure of the massage-unit against his body.

60 The massage-unit, if desired, may be disconnected from the other part of the apparatus by loosening the nut 45 and used manually on parts of the body which cannot be conveniently reached when the unit is secured to the rest of the device.

In Figs. 7 to 9 inclusive I show a form of the invention which is manually operated. The arm 42 of the massage-unit 41 extends into a socket 90 and may be locked therein by a screw-clamp 91. The arm 90 has a clevis 93 at one end thereof which swings on a pivot-bolt 94. The pivot-bolt 94 is supported by a bracket 96. The bracket 96 has a U-shaped member 97 which surrounds a vertical rod 98, the vertical rod 98 being secured to a wall or other suitable support by brackets 99. The U-shaped member 97 may be clamped tightly on the rod 98 by a screw 100 so that the arm 92 is supported at the desired level.

70 The massage-unit 41 has handles 103 hinged thereto at 104. These handles may swing from full line position as shown in Figs. 8 and 9 into dotted line positions 105 as shown in Fig. 8. When using this form 75 of the invention, the massage-unit must be manually swung. When using the massage-unit on the back, the handles 103 are moved into the position shown in Fig. 9 so that the user may place his hands on the extending ends 106 of the massage-unit and swing it up 80 and down. The form of the invention just described and shown in Figs. 7 to 9 inclusive includes all the features of the form of the invention described first, with the exception 85 of the means for mechanically swinging the 90 massage-unit.

95 I claim as my invention:

1. A massaging device comprising: a frame; a plurality of shafts carried by said frame; rollers carried by said shafts, the rollers on adjacent shafts being out of alignment and having rounded peripheries; an arm extending rearward from said frame; pivot means for pivoting the end of said arm; and foldable handles connected to said frame, said handles being extendible so that they may be manually engaged for swinging said arm.

100 2. A massaging device comprising: a frame; massaging elements on said frame; a base; means pivotally connecting said frame with said base; and handles pivotally provided on said frame, said handles being foldable to conform to the shape of said frame.

105 3. A massaging device comprising: a frame; massaging elements on said frame; a base; means pivotally connecting said frame with said base; and handles hingedly connected to said frame for extension beyond the free end thereof and foldable backwardly to close proximity with each other in position to be gripped by one hand of the operator.

110 4. A massaging device comprising: a base; a frame; pivot means for pivotally connecting said frame to said base; a plurality of relatively spaced substantially parallel massaging rollers journaled on the forward free-end portion of said frame, the axes of said rollers being disposed on an arc generated from a center located between said rollers and the pivotal center of said connecting 115 120 125 130

means; and handle means connected to said frame for moving said rollers against a surface to be massaged.

5. A massaging device comprising: a base; a frame pivoted to said base; a plurality of shafts pivotally mounted in the free end of said frame, the axes of said shafts lying on an arc the center of which lies between said shafts and the axis about which said frame is pivoted; and massaging rollers mounted on said shafts.

6. A massage device comprising: a frame; massaging elements on said frame; a base; means pivotally connecting said frame with said base, said means being adjustable vertically on said base; and handles provided on said frame, said handles being foldable to conform to the shape of said frame.

7. A massage device comprising: a frame; massage elements on said frame; a base; an arm pivotally connecting said frame with said base, said arm being adjustable on said base; and foldable handles connected to said frame, said handles being extendible so that they may be manually engaged for swinging said arm.

In testimony whereof, I have hereunto set my hand at Los Angeles, California, this 17th day of May, 1927.

30 ANTHONY E. CARLSON.
